UNITED STATES PATENT OFFICE.

SAMUEL STEWART FLETCHER, OF NOTTINGHAM, ENGLAND.

MILANESE MACHINE.

Application filed March 26, 1927, Serial No. 178,704, and in Great Britain March 29, 1926.

This invention relates to improvements in warp knitting machines of the kind known as Milanese machines, in which a travelling warp is knitted into a looped fabric. Its object is to provide facilities whereby the warp-threads can be divided into two or more distinct sets, so that threads of different thicknesses, as well as threads of different materials, can be embodied in such fabrics, and varying tensions be put upon the different sets into which the warp-threads are divided. By providing the additional facilities described, entirely new ornamental effects can be produced.

In a Milanese machine, two warp-threads are provided in connection with each needle, that is, one in a front set and another in a rear set, and the front set travel along the needles in one direction and the rear set travel in the reverse direction.

In order to effect this result, the warp-threads are wound on a number of very short warp-beams, each of the latter is mounted in a carriage, and a number of the latter are joined together so as to form an endless chain comprising a front and back set extending from one end of the machine to the other joined together at the ends so that they can move round continuously. There are thus two rows of travelling warp-beams, one moving in the reverse direction to the other from which the two sets of threads are drawn, and means are provided for imparting the requisite travelling movement to this endless chain of warp-beam carrying carriages.

Threads of different materials or of different colours may be used with the present system, but owing to the fact that all the thread supplied to the needles must be taken from the same set of travelling warp-beams, it is not possible to introduce threads of different thicknesses, as winding threads of different thicknesses side by side on the same warp-beam, would present insuperable difficulties when it came to working the threads off the same again, as the thick threads naturally build-up quicker when wound on the warp-beam, and consequently overlay and prevent the withdrawal of the finer threads.

According to this invention, each carriage in the endless chain is fitted with two or more short warp-beams, and each of the latter is provided with independent thread tension mechanism, so that the threads wound on one of the warp-beams in each carriage, can not only be of a different size, but can be ten-

sioned to a more or less extent than those wound on the other warp-beam in the same carriage.

Referring to the accompanying drawings. Fig. 1 is a side elevation, and

Fig. 2 a plan of one of the traversing warp-beam carriages, fitted with two warp-beams according to our invention.

Fig. 3 is a plan, drawn to a smaller scale than Figs. 1 and 2, showing a series of warp-beam carrying carriages jointed together.

Like letters indicate like parts throughout the drawing.

As shown in the drawings, each travelling warp-beam carriage is comprised of a base A with standards B at each side, and each is in the example shown adapted to carry two independent short warp-beams C and D, which are for convenience disposed one above the other. These warp-beams are both of the usual construction, each being comprised of a plain cylindrical part on which a number of threads can be wound, with flanges at its ends to prevent the threads from falling down.

The upper warp-beam C, is mounted in bearings E provided for it in the standards B, and the threads M thereon are carried from this warp-beam, under a roller F, and then up to and through the thread sley-plate G, which latter is carried at the requisite height on a pillar H secured to the base A of the carriage.

The lower warp-beam D, is mounted in bearings J provided for it in the standards B below those E provided for the upper warp-beam, and the threads N thereon are carried from this warp-beam D under a second roller K, and then up to the same thread sley-plate G as the threads M.

The journals of the rollers F and K, are mounted in vertically slotted bearings O and P respectively in the standards B, and they are held down therein by means of spring actuated plungers L, which permit of the said rollers rising to a limited extent, and thus relieving when necessary, the strain on the respective sets of threads M and N.

Tension is put upon the threads M and N disposed upon the respective upper and lower warp-beam sections C and D, by the following arrangement. A grooved pulley R (see Fig. 2) is provided on each of the warp-beams, a cord Q is carried round the pulley R, and a weighted brake-lever S is pivoted to the standard B. One end of the cord Q is

anchored to a fixed point, its other end is attached to the brake-lever S, and the latter is fitted with an adjustable weight T.

Independent but identical thread tension means is thus provided in connection with each of the warp-beams C and D, in the whole of the travelling carriages, and the tension on the respective sets of threads M and N can be regulated by the adjustment of the weights 5 T placed on the respective brake levers S. Accommodation can be made for further warp-beams, by raising the height of the standards B, and it will be understood that by increasing the number of the warp-beams, 10 their size can be reduced without detriment, as a less number of threads have to be wound on each.

The provision of two or more warp-beams in each travelling carriage as described, will 20 permit of the introduction into the machine of threads of different sizes, and they can be distributed at any desired intervals. The threads of each size are wound on the corresponding warp-beams in each of the carriages 25 A, and as each set of threads is thus taken from an independent supply, they can not only be considerably different in size, but the tension on each set can be independently adjusted to produce the desired result, by means 30 of the separate and distinct thread tension mechanism provided in each case.

As an example of the class of ornamental fabrics which can be produced, groups of coarser threads than the remainder may be 35 introduced at regular intervals, and as the whole of the threads travel as usual, the coarser threads form diagonal stripes in the work, but in addition to this, the coarser threads in the front set for the time being 40 form diagonal stripes which run in the reverse direction to those formed by the coarser threads which are at the time in the rear set, and the said stripes therefore cross and form a diamond pattern.

45 The stripes are owing to the coarser thread embodied therein, thicker than the spaces between them, and where they cross, the fabric

is still thicker, and a distinct pattern is thus formed which is irrespective of colours.

Coloured threads, or different classes of threads which may be subsequently dyed different colours, may however be introduced in combination with the different sized threads, thereby affording a greater range of different designs, which can be still further 50 varied by regulating the tension on these threads on one set of warp-beams, relatively to the tension of those on the other set or sets, whereby different effects can be produced.

What I claim as my invention and desire 60 to cover by Letters Patent is:—

1. In a Milanese machine, a series of carriages operatively connected together for motion in one direction, each carriage being provided with a plurality of warp-beams which 65 are moved with it and on which the warp-threads are distributed in distinct sets.

2. A Milanese machine provided with carriages and warp-beams as set forth in claim 1, each warp-beam being provided with a separate 70 thread tensioning device.

3. In a Milanese machine, a series of carriages operatively connected together for motion in one direction, each carriage having 75 standards secured to it, and a plurality of warp-beams journaled in the standards of each carriage.

4. A Milanese machine as set forth in claim 3, each warp-beam having a separate thread tensioning device operatively connected with 80 its journal.

5. In a Milanese machine, a series of carriages operatively connected together for motion in one direction, each carriage being provided with a plurality of warp-beams which 85 are moved with it, a thread sley-plate supported by each carriage, and a plurality of spring-pressed rollers supported by each carriage and operating to guide the warp-threads to the said sley-plate.

90 In testimony whereof I have affixed my signature.

SAMUEL STEWART FLETCHER.
